UNITED STATES PATENT OFFICE.

DEXTER J. CALDWELL, OF GUNN, VIRGINIA.

CAR-COUPLING.

SPECIFICATION forming part of Letters Patent No. 359,710, dated March 22, 1887.

Application filed December 18, 1886. Serial No. 221,977. (No model.)

To all whom it may concern:

Be it known that I, DEXTER J. CALDWELL, a citizen of the United States, residing at Gunn, in the county of Craig and State of Virginia, have invented a new and useful Improvement 5 in Car-Couplings, of which the following is a specification.

My invention is an improved car-coupling, the novelty of which consists of the construction and arrangement of parts, as hereinafter fully described, and particularly pointed out in the claims.

The object of my invention is the provision of a car-coupling which couples automatically, 15 and thereby avoids the dangerous expedients heretofore resorted to by the attendant passing between the cars at the risk of his life to effect the coupling.

A further object is the provision of simple 20 and very easily-operated means for uncoupling the cars, and further to improve the car-coupling in minor details to render the same simple, strong, and durable in construction and cheap of manufacture.

In order that my invention may be fully 25 and clearly understood and its merit and value be appreciated, I have illustrated a car-coupling embodying my invention in the accompanying drawings, which represent, in—

Figure 1, a side elevation of a pair of draw-heads provided with my automatic coupling means attached in position to the cars. Fig. 2 represents a longitudinal sectional view of the draw-heads, illustrating the coupling-link 30 of the approaching car entering the draw-head to effect the coupling. Fig. 3 represents a transverse sectional view of my car-coupling, and Fig. 4 is a detached perspective view of the follower.

Referring to the drawings, in which similar letters of reference denote corresponding parts in the several figures thereof, A designates portions of railway-cars to which are attached draw-heads B, of the ordinary or any preferred 40 pattern, and in connection with which I employ my automatic coupling means. On the upper face of the draw-heads are formed, integral therewith, or in any preferred manner secured thereto, barrels, tubes, or casings C, provided with detachable caps, c, which are formed with central aligned openings c', through which pass the coupling-pins D. The caps c are

threaded exteriorly to screw into the tubes. The central aligned openings, c', are also in line with the openings b of the draw-heads, for the 55 purpose to be explained.

Around the coupling-pins D in the tubes or barrels C are coiled springs E, which give the coupling-pins a spring-action. The upper ends of the springs bear against the caps c, 60 while their lower ends bear upon a pin or extension of the coupling-pin. The upper ends of the said coupling-pins are provided with openings or eyes d, which receive the ends of rods F, that extend upwardly through openings g in horizontal arms G, secured to the cars, and the upper ends of the said rods F are preferably formed with a hook, loop, or handle, f, to permit of the easy manipulation 65 of the said rods F.

From this construction it will be readily seen that the coupling-pins have a downward spring action, and can be elevated or raised by the rods F for the purpose of uncoupling the cars, as will be presently explained.

In the chambers or passages of the draw-heads B are placed the followers H, which are constructed with the angular heads h, provided with the curved grooves h' on their front portions, and at the rear portion of the follower-heads h are provided arms or rods h', around which are placed coiled springs I, and the arms h' are adapted to work back and forth in openings b', provided in the rear walls of the chambers of the draw-heads. These spring-actuated followers H are limited in their forward movement by the contact or stop blocks J, secured by bolts to the upper inner faces of the mouths of the draw-heads, as clearly shown.

This being the construction of my car-coupling, the operation consequent upon the same is as follows: The rods F are elevated, causing the followers to move forward against the stop or contact blocks and the coupling-pin to rest on the upper portion of the heads of the followers. In this position the coupling-link of the approaching draw-head enters the flaring mouth of the draw-head and strikes in the cut-out portion of the follower, driving the same backward until the follower clears the lower end of the coupling-pin, when the spring-actuated coupling-pin shoots downward through the openings in the draw-head and thereby confines the coupling-link in the draw-head,

thus automatically coupling the cars. To uncouple the cars, it is only necessary to raise the coupling-pins by means of the rods F, the follower springing forward against the stop-blocks and supporting the coupling-pins in their elevated position, as will be readily understood.

5 The many advantages of my car-coupling will be readily understood by all skilled in the art from the foregoing description, taken in connection with the drawings, and need no further comment.

I claim—

15 1. A car-coupling comprising a spring-actuated follower working in the draw-head, a stop-block bolted to the upper inner face of the draw-head, in the mouth thereof, and a spring-actuated coupling-pin mounted above the draw-head, substantially as set forth.

2. The herein-described car-coupling, comprising the draw-head having a stop bolted to its upper inner face at its mouth, the spring-actuated follower-block working in the draw-head and having an arm extending rearwardly therefrom into the rear end of the draw-head, a barrel erected upon the draw-head, and a spring-actuated coupling-pin working in said barrel, substantially as specified.

20 In testimony that I claim the foregoing as my own I have hereto affixed my signature in presence of two witnesses.

DEXTER J. CALDWELL.
